CENTRALIZED TRAFFIC CONTROLLING
SYSTEM FOR RAILROADSNeil D. Preston, Rochester, N. Y., assignor to
General Railway Signal Company, Rochester,
N. Y.

Application May 16, 1936, Serial No. 80,095

8 Claims. (Cl. 177—353)

This invention relates to centralized traffic controlling systems for railroads and it pertains more particularly to the communication part of such systems.

5 In railroad traffic controlling systems the traffic is controlled from a control office usually located at a central point with respect to an outlying field station or a plurality of field stations. The field station or stations are connected to the control office by means of the communication system. The location of trains and the condition of the various traffic controlling devices at the outlying field station or stations are indicated to the attendant in the control office. These indications relating to the condition of the traffic controlling devices and the like are transmitted to the control office by means of the communication system.

The present invention is particularly useful in 20 a system which is called upon to carry out a relatively large number of controls and indications during a short time. The present embodiment more particularly relates to a system comprising a control office and a single station although it 25 will be understood that the invention is not limited to a single station.

The communication system provided interconnects the control office and the field station and it is so organized that complete control and supervision of the various devices, such as the track switch and the signals therefor, are obtained by the operator. Such a traffic controlling system is supplemented by the usual automatic block signal system and other local means ordinarily 35 provided to guard against unsafe train movements, improper operation of track switches and the like.

In accordance with the preferred form of the present invention (Figs. 1, 2 and 3) the communication system comprises a four wire line circuit extending from the control office to the outlying field station. These four line wires are referred to in this disclosure as the S line, the C line, the A line and the B line. The S and the 45 C lines form a circuit over which stepping impulses are transmitted and over which control code combinations are transmitted. The A and B line conductors are arranged to be selectively connected to the S and C line conductors for the transmission of indications. The C line conductor is therefore a common conductor for the S line circuit and for the circuits made up, including the A and B line conductors.

For the transmission of indications, the A line 55 circuit is energized with impulses of distinctive

character (polarity) as determined by the selective connection of the A line to the S line and the C line at the station. This selective connection provides a choice of two indications for each step of the stepping mechanism. Additional indications are transmitted by selectively connecting the B line to the S line and the C line at the station. This selective connection of the B line circuit also provides a choice of two indication conditions for each step of the stepping mechanism. Thus a choice of four indication conditions is provided on each step.

This selective energization of the A and B line circuits is controlled at the field station from energy supplied by the control office line battery, 15 irrespective of the polarity with which the S line and the C line is energized as selected at the control office. The selective energization of the A and B line circuits is consequently determined at the transmitting field station in proper co- 20 relation with the polarity of energization of the S and C line conductors at the control office, all of which will be pointed out in the detailed description which follows.

For convenience in describing the operation 25 of this system the energized periods of the S line circuit will be referred to as the "on" periods and the deenergized periods of the S line circuit will be conveniently referred to as the "off" periods. In the first modification, all line circuits are 30 normally deenergized. At the start of a control cycle the S line circuit is energized with a (+) impulse for conditioning the circuits and after these circuits are properly conditioned the system steps through an operating cycle in a manner which will be described in detail. When the 35 system is initiated from the field station the A line circuit is energized with a (+) impulse for conditioning the circuits of the system, after which the system steps through a cycle of operations as will be explained in detail.

In accordance with a modification (Figs. 4, 5 and 6), use is made of a five wire line circuit, over which double the number of controls and indications (compared with the system of Figs. 45 1, 2 and 3) are transmitted. The same fundamental principle used in the system already described, that is, the use of polar impulses derived from a source of current in the control office for the transmission of indications, is used in this 50 modification.

The schematic circuit diagram of Fig. 4 indicates the five wire line circuits and the apparatus most closely associated with these line circuits. The S line, in combination with the A 55

and B lines forming return paths for impulses in the S line, is used for controlling the stepping operation and for transmitting a choice of two controls at each step. The A line in combination with the B line as a return conductor is used for transmitting a choice of two additional controls for each step. As indicated in the control office portion of this figure, line battery LB supplies energy for the transmission of stepping impulses and one set of controls, the polarities 10 of which are determined by the PC and NC relays. The controls transmitted over the A line circuit are made up of impulses from the source of current 2LB, with the polarity determined by 15 relay PX.

A choice of four indications is provided during the "off" periods by energizing the MA and MB line circuits with polar impulses selected at the field station, the polarity of which is supplied 20 from battery 2LB in the control office being connected to the A and B line conductors. These four "off" indications are selected through back contacts of relay FP¹ at the field station as indicated by the legends "to MAB (and to MBB) 25 indication circuits selected by stepping relays". This refers to the fact that the MA and MB lines are conditioned through back contacts of 30 relay FP¹. The back contacts of relay FP in the control office connect to relays MAB and MBB, which relays are operated by the polar impulses applied to the respective line circuits.

During the "on" periods, when relays FP and FP¹ are picked up, additional indication circuits are selected as indicated by the legends which refer to the MAF and MBF indication circuits. 35 The front contacts of relay FP in the office lead through relays MAF and MBF so that these relays may be selectively operated in accordance with the polar impulses applied to the MA and 40 MB lines respectively.

Other objects and advantages of the present invention will be hereinafter set forth in the specification and claims and further details will be understood by referring to the accompanying 45 drawings which illustrate the different methods of carrying out the invention by way of example.

The drawings illustrate in a diagrammatic manner the apparatus and circuits employed and 50 for convenience in describing the invention those parts which have similar features and functions are designated in the different figures by like reference characters, generally made distinctive by the use of distinctive exponents representative of their location and by the use of suitable preceding numerals representative of the order 55 of their operation and in which:—

Fig. 1 illustrates in a schematic manner the arrangement of the line circuits, which connect the control office with the field station, showing 60 only the apparatus most closely associated with the line circuits.

Fig. 2 illustrates in more detail the apparatus and circuit arrangement employed at the control office for providing means whereby an operator may govern the switches and signals at the field station and whereby indications may be received in the control office from the field station.

Fig. 3 illustrates the apparatus and circuit arrangement of the preferred form somewhat in detail, as employed at the field station for providing control of a single track switch and for transmitting indications to the control office in accordance with the present invention.

When tracing the detailed circuits of the first

modification, Fig. 3 should be placed to the right of Fig. 2 with correspondingly numbered lines in alinement.

Fig. 4 illustrates in a schematic manner the arrangement of the line circuits (of the modification) 5 which connect the control office with the field station, showing only the apparatus most closely associated with the line circuits.

Fig. 5 illustrates in more detail the apparatus and circuit arrangement (of the modification) 10 employed at the control office for providing means whereby an operator may govern the switches and signals at the field station and whereby indications may be received in the control office from the field station. 15

Fig. 6 illustrates the apparatus and circuit arrangement somewhat in detail (of the modification), as employed at the field station for providing control of a single track switch and for transmitting indications to the control office in 20 accordance with the present invention.

When tracing the detailed circuits of the modification, Fig. 6 should be placed to the right of Fig. 5 with correspondingly numbered lines in alinement. 25

For the purpose of simplifying the illustrations and facilitating in the explanation, various parts and circuits have been diagrammatically shown and certain conventional illustrations have been employed. The drawings have 30 been made more with the purpose of making it easy to understand the operation of the invention than with the idea of illustrating the specific construction and arrangement that would preferably be employed in practice. 35

The symbols (+) and (−) are employed to indicate the positive and negative terminals respectively of suitable batteries or other sources of current and the circuits with which these symbols are used have current flowing in the 40 same direction, that is, from (+) to (−). The symbols (B+) and (B−) are employed to indicate the positive and negative terminals respectively of a suitable battery or other source of current having a mid-tap (CN) and the circuits 45 with which these symbols are used may have current flowing in one direction or the other depending upon whether the terminal (B+) or (B−) is used in combination with tap (CN).

Control office equipment, preferred form.—The 50 control office (see Fig. 2) includes a control machine having a group of control levers associated with the field station, a miniature track layout corresponding to the track layout at the station and various indicating lamps or equivalent devices, together with apparatus and circuits to accomplish the desired operation of the system. 55

The apparatus for a single track switch at the field station comprises a switch machine control lever SML, a self-restoring starting button 60 SB, a miniature track switch ts and a track occupancy indicating lamp OS. It will be understood that one or more additional switch machine levers may be provided if a plurality of track switches are located at the field station. 65 It will also be understood that one single starting button SB per station is used, irrespective of the number of control levers provided.

Similarly, one or more signal control levers are provided but for convenience only a single 70 signal control lever SGL has been illustrated, since the control of the circuits by additional levers may readily be understood after an explanation of the control by the illustrated levers, by way of example.

The control office includes a line relay F and a line repeating relay FP of the neutral quick acting type. A slow acting line repeating relay SA is controlled by relay FP to define the bounds of 5 a cycle of operations, that is, relay SA is picked up at the beginning of a cycle, remains picked up throughout the cycle and is dropped after a predetermined period of time has been measured off following the last impulse at the end of the 10 cycle.

Associated with the line repeating relays is a bank of stepping relays including half-step relay VP and stepping relays 1V, 2V, 3V and LV. This 15 bank of stepping relays is for the purpose of marking off the successive steps of each cycle.

A starting relay STR starts the system into a cycle of operations in response to the initiation of a code call either from the control office or from the field station. Change relay CH² is 20 picked up in response to the actuation of button SB and this relay serves the purpose of initiating the system from the control office.

The S line circuit is energized with (+) or (-) impulses from line battery LB in accordance 25 with the operation of code sending relays PC and NC. More specifically, the S line circuit is energized with a (+) impulse when relay PC is picked up and with a (-) impulse when relay NC is picked up. This polarity of energization 30 is determined during the "off" periods and upon the picking up of the selected code sending relay PC or NC, the S line circuit is energized with the selected polarity.

Message receiving relays MA and MB of the 35 biased to neutral polar type are connected in the A and B line circuits respectively and are for the purpose of receiving messages in the control office in accordance with the indications being transmitted from the field station.

40 Indication receiving relays 1IR and 2IR are provided to receive the indication which is transmitted from the field station at the particular steps of the cycle, as selected by the operation of the stepping relay bank in the control office.

45 These relays are of the polar magnetic stick type, that is, their contacts remain in the positions to which they were last actuated until shifted by the energization of their windings with an impulse of opposite polarity. Relay 1IR receives 50 the indication as to whether or not the track section at the field station is occupied and indicates this condition by energizing or de-energizing lamp OS. Relay 2IR may receive any other indication required, but since the operation 55 of relay 1IR is typical of the operation of other indication receiving relays, the control of indicating devices by relay 2IR is not shown. Resistance R is for the purpose of protection against short-circuiting the battery in the event of an 60 improper adjustment of the PC and NC relay contacts.

65 *Field station equipment, preferred form.*—The field station (see Fig. 3) comprises a turnout track connected to a main track by means of a track switch TS. This track switch is operated from one extreme locked position to the other by a suitable switch machine SM. The switch machine is controlled by a switch machine control 70 relay SMR of the two-position polar magnetic stick type and this relay is governed from the control office through the medium of the communication system herein disclosed. Relay SMR controls the operation of the switch machine by 75 energizing its normal or reverse operating wires

from a local source of current as controlled by contact 400. This control preferably includes suitable approach locking and other automatic signaling means as usually employed but not shown in the present disclosure for the sake of simplicity.

Suitable signals are associated with track switch TS for governing traffic thereover. These signals are also governed from the control office through the medium of the communication system in any suitable way by means of control relays such as relay SGR, operated from the control office in a similar manner as switch machine control relay SMR. The detailed circuit arrangement of the signal control at the field station has been omitted from the present disclosure since it is immaterial for an understanding of the present invention.

The detector track section has a normally closed track circuit with the usual track battery 20 and track relay T for indicating the passage of trains.

The communication part of the system includes control line relay F¹ of the quick acting, biased-to-neutral, polar type and resistance R¹. The 25 S line conductor is connected to the C line conductor in series with resistance R¹ in order to provide the necessary drop in potential for energizing relays MA and MB during the transmission of indications. Quick acting relay FP¹ and 30 slow acting relay SA¹ are the line repeating relays at the station, similar to corresponding relays in the control office.

The field station includes a bank of stepping relays, comprising half-step relay VP¹ and stepping relays 1V¹, 2V¹ and 3V¹ which operate substantially in synchronism with corresponding relays in the control office. Since the circuit arrangement for operating this bank of stepping relays may be the same as that shown in detail 40 for the control office bank of stepping relays, the detailed circuit arrangement has only been indicated by the dotted line extending from front contact 420 of relay SA¹ to the stepping relay bank.

45 A change relay CH¹ is provided to register a change in condition of any of the traffic controlling devices at the station so that the system will be initiated for the transmission of new indications. The detailed control of this relay has 50 not been shown since it is well known in the art how such a relay is made responsive to a change in condition of traffic controlling devices and re-sensitized during the succeeding cycle of operations so that it may respond to the next change.

The A line impulse relay PLA and the B line impulse relay PLB are provided for selectively connecting the A and B lines respectively to the S and C lines as determined by the condition of the traffic controlling devices and these conditions are transmitted to the control office by means of indication codes made up by the selective operation of the PLA and PLB relays.

65 For the purpose of indicating how the different indication conditions are transmitted by the energization or the de-energization of relays PLA and PLB, relays M and T are provided. Relay M may be the usual signal indicating relay which is energized when all of the signals are at stop and de-energized when some one of the signals is in its proceed condition. Relay T is the track relay energized when the associated track section is unoccupied and de-energized when this track section is occupied.

Operation of preferred form

The system is normally in a condition of rest, from which it may be initiated into a cycle of operations either from the control office or from the field station when there are new controls or new indications ready to transmit.

Irrespective of whether a cycle is to be for the transmission of controls or the transmission of indications, a predetermined number of impulses 10 are placed upon stepping line S to accomplish the step-by-step operation of the stepping relay banks. These impulses are time spaced, that is, they follow each other at definite time intervals.

When a cycle is initiated for the transmission 15 of controls the character of the impulses placed upon the S line circuit is determined in accordance with the positions of the control levers in the control office. During such a cycle, indications are transmitted by means of the character 20 of the impulses placed upon the A and B line circuits as determined by the positions of the control devices at the field station, as repeated by relays T and M for example.

When a cycle of operations is initiated from 25 the control office, a series of indications are transmitted from the station to the office irrespective of whether a change in condition of the control devices has taken place or not. Likewise, when a cycle of operations is initiated from 30 a field station, the position of the contacts of the control levers in the office at that time are transmitted to the field station irrespective of whether the starting button in the control office has been actuated or not. It will thus be seen 35 that the present invention provides for the duplex operation of the system, that is, controls and indications are transmitted during a single cycle of operations.

Normal conditions, preferred forms.—Although 40 the system may be initiated from the field station all line circuits are normally de-energized. In order to provide a means for initiating the system from the station the normally de-energized A line circuit is energized in response to the 45 dropping of change relay CH¹. Relay CH¹ is in its normally energized condition as previously mentioned and track relay T is normally energized when the associated track section is unoccupied. The remaining circuits of the system, 50 both at the field station and at the control office, are normally de-energized.

Manual start, preferred form.—With the system in a condition of rest it is manually initiated into a cycle for the transmission of controls by 55 the actuation of starting button SB after the control levers have been suitably positioned.

For the purpose of considering the operation 60 of the present invention it will be assumed that lever SML is in its right hand normal position and that lever SGL is in its center stop position. The actuation of button SB closes a circuit for picking up relay CH² which extends from (+), contact 310 of button SB and winding of relay CH² to (-). Relay CH² closes a stick circuit for 65 itself extending from (+), back contact 311 of relay SA, front contact 312 and winding of relay CH², to (-).

The picking up of relay CH² closes a circuit for 70 picking up relay STR which extends from (+), back contact 313 of relay SA, back contact 314 of relay LV, front contact 318 of relay CH² and lower winding of relay STR, to (-). Relay STR closes a stick circuit for itself extending from 75 (+), back contact 319 of relay LV, front contact

320 and upper winding of relay STR, to (-). The picking up of back contact 321 of relay STR disconnects the C line conductor from the circuit leading to back contact 322 of relay PC and front contact 323 of relay NC, so that the closure of 5 front contact 324 and the opening of back contact 321 of relay STR places the energization of the S line circuit under the control of the pole changing contacts of relays PC and NC.

The S line circuit is energized with (+) potential because relay PC is now picked up over the circuit extending from (+), back contacts 325, 326 and 327 of relays 3V, 2V and 1V respectively, PC bus, winding of relay PC, front contact 328 of relay STR, back contacts 329, 330, 331 and 332 of 15 relays VP, 1V, 2V and 3V respectively, to (-). The energizing circuit for the S line circuit extends from the (+) terminal of battery LB, front contact 333 of relay PC, back contact 323 of relay NC, front contact 324 of relay STR, winding of relay F, S line conductor 334, winding of relay F¹, resistance R¹, C line conductor 35, back contact 336 of relay NC and front contact 322 of 20 relay PC, to the (-) terminal of battery LB.

The circuit from battery LB (above traced) 25 branches at the field station from S line conductor 334 where it may be traced through front contact 422 of relay SA¹ (picked up as later described), back contacts 401 and 402 of relays PLB and PLA respectively, B line conductor 50 30 and A line conductor 40 in multiple, windings of relays MA and MB to the center tap of battery LB. Current flowing over this circuit is in such a direction that the polar contacts of relays MA and MB are operated to their left hand dotted 35 positions and since polar contacts 54 and 62 of relays MA and MB connect to the channel selecting circuit arrangement of the stepping relays and since none of these relays are as yet operated, the actuation of these contacts is ineffective at this time. Since polar contact 52 of relay MA is actuated to its left hand dotted position, this operation is ineffective to close any local energizing circuits. Relay F¹ is energized over the above described circuit and its polar 45 contacts are positioned to the right for closing a circuit for picking up relay FP¹ which extends from (+), contact 410 of relay F¹ in its right hand dotted position and winding of relay FP¹, to (-). Relay FP¹ closes an obvious circuit 50 through its front contact 411 for picking up relay SA¹.

The energization of the S line circuit causes 55 relay F to pick up and close its front contact 37 for energizing relay FP over an obvious circuit and relay FP closes an obvious circuit at its front contact 38 for energizing relay SA. The opening of back contact 311 of relay SA de-energizes 60 the stick circuit of relay CH², which allows this relay to drop.

Step-by-step and impulsing operations of preferred form.—The energization of relay SA closes a circuit for picking up relay VP which extends from (+), front contact 311 of relay SA, front contact 41 of relay FP, back contacts 42, 43 and 44 of relays 3V, 2V and 1V respectively and winding of relay VP, to (-). Relay VP closes a 65 first stick circuit for itself extending from (+), front contact 311 of relay SA, front contact 51 of relay VP and over the remainder of the previously described circuit to the winding of relay VP.

The picking up of relay VP opens, at its back contact 329, the previously described energizing circuit for relay PC which allows this relay to 70 75

drop for de-energizing the S line circuit at contacts 322 and 333. This effects the dropping of relays F and FP in the office and relays F¹ and FP¹ at the field station. A second stick circuit is now completed for relay VP which extends from (+), front contact 311 of relay SA, back contact 41 of relay FP, front contact 45 and winding of relay VP, to (-).

A pick up circuit for relay 1V is now closed which extends from (+), front contact 313 of relay SA, back contact 46 of relay FP, front contact 47 of relay VP, back contact 316 of relay 2V and winding of relay 1V, to (-). Relay 1V closes an obvious stick circuit for itself at its front contact 339.

Relay PC (or relay NC if selected by the control lever contacts) will now be picked up over a circuit extending from (+), back contacts 325 and 326 of relays 3V and 2V respectively, front contact 327 of relay 1V, contacts of lever SML, winding of relay PC, front contact 328 of relay STR, front contact 329 of relay VP, front contact 330 of relay 1V, back contacts 331 and 332 of relays 2V and 3V respectively, to (-).

The selected PC (or NC) relay energizes the S line circuit for again picking up relays F and FP, after which relay VP is de-energized because its first stick circuit is open at back contact 44 of relay 1V and its second stick circuit is open at back contact 41 of relay FP. The dropping of relay VP de-energizes the selected PC (or NC) relay by reason of open front contact 329.

With both relays PC and NC de-energized the S line circuit is de-energized, resulting in the dropping of relays F and FP to cause the picking up of relay 2V over a circuit extending from (+), front contact 313 of relay SA, back contact 46 of relay FP, back contact 47 of relay VP, back contact 315 of relay 3V, front contact 317 of relay 1V and winding of relay 2V, to (-). Relay 2V closes an obvious stick circuit for itself at its front contact 48.

The closure of front contacts 326 of relay 2V closes an energizing circuit for the PC or NC relay as selected by lever SGL. Upon the response of the selected PC or NC relay the S line circuit is again energized and relays F and FP are picked up. Relay VP is now picked up over a circuit extending from (+), front contact 311 of relay SA, front contact 41 of relay FP, back contact 42 of relay 3V, front contact 43 of relay 2V and winding of relay VP, to (-). Relay VP again closes its first stick circuit which will be obvious from the circuit previously traced.

The picking up of relay VP opens the energizing circuit of the PC and NC relays so that the selected one of these relays is dropped to de-energize the S line circuit. This effects the dropping of relays F and FP so that a circuit is closed for picking up relay 3V, extending from (+), front contact 313 of relay SA, back contact 46 of relay FP, front contact 47 of relay VP, front contact 316 of relay 2V and winding of relay 3V, to (-). Relay 3V closes an obvious stick circuit for itself at its front contact 49. The closure of back contact 41 of relay FP again completes the second stick circuit for relay VP as previously described.

The picking up of relay 3V closes a circuit by way of its front contact 325 for energizing relay PC or relay NC (as selected by a control lever such as lever SGL). This results in the energization of the S line circuit for picking up relays F and FP. Relay VP is now dropped because its first stick circuit is open at back contact 42 of relay

3V and its second stick circuit is open at back contact 41 of relay FP.

The dropping of relay VP opens the energizing circuit of the selected PC or NC relay at open front contact 329 which results in both the PC and NC relays being de-energized. This de-energizes the S line circuit for dropping relays F and FP. A circuit is now closed for picking up relay LV which extends from (+), front contact 313 of relay SA, back contact 46 of relay FP, back contact 47 of relay VP, front contact 315 of relay 3V and winding of relay LV, to (-).

Since relay LV does not change the energizing circuit for the selected PC or NC relay, both of these relays remain de-energized because the circuit extending to (-) at front contact 332 of relay 3V is interrupted at front contact 329 of relay VP. This results in relays F and FP remaining de-energized for a sufficiently long period of time to release relay SA. The dropping of relay SA de-energizes the stick circuits of the stepping relays and starting relay STR at its front contact 313, with the result that these relays are dropped.

Since relay LV is slow acting, the (+) potential applied to the stick circuit of relay STR is removed for a period of time sufficient to allow this relay to drop its contacts and shortly thereafter relay LV closes its back contact 319 for again energizing this stick circuit in preparation for the next cycle.

From the above description it will be understood that relays F¹ and FP¹ operate substantially in synchronism with relays F and FP and as above mentioned, the response of these line repeating relays at the field station effects the operation of the stepping relay bank at the field station in synchronism with the stepping relay bank in the control office. The stepping relays at the station are similarly de-energized when relay SA¹ drops in response to the last long "off" period of the stepping line circuit to de-energize the stepping relay stick circuit.

Polarity selection of control impulses, preferred form.—When the system is initiated from the control office as above described the first (conditioning) impulse applied to the S line circuit is (+) in character by reason of the picking up of relay PC. This application of energy to the S line circuit causes various relay operations which have already been described.

Assuming that the switch machine lever is in its right hand normal position as shown, the first impulse applied to the S line circuit (following the conditioning impulse) is (+) as already described. In the event that lever SML is in its left hand dotted reverse position, relay NC is picked up over a circuit extending from (+), back contacts 325 and 326 of relays 3V and 2V respectively, front contact 327 of relay 1V, contact of lever SML in its left hand dotted position, NC bus, winding of relay NC, front contact 328 of relay STR, front contact 329 of relay VP, front contact 330 of relay 1V, back contacts 331 and 332 of relays 2V and 3V respectively, to (-). The energization of relay NC applies a (-) impulse to the S line circuit.

This selection of the polarity of energization for the S line circuit occurs on each step by reason of the selection made at front contacts 327, 326 and 325 of relays 1V, 2V and 3V respectively. This selection energizes relay PC or NC in accordance with the particular position of the control lever selected for each step. It will be understood that additional levers for other control purposes may be provided and selected through addi-

tional contacts of additional stepping relays when the size of the system requires such extra selection.

From the above it will be seen that the impulse applied to the S line circuit during the conditioning period of a cycle initiated in the control office is (+), with the following impulses applied to the S line circuit being (+) or (-) in character dependent upon the positions of the control levers rendered effective by the stepping 10 relays at the various steps of the cycle. This polarity determination is accomplished by two code sending relays PC and NC which are selectively energized during the "off" periods of the S line circuit for controlling the succeeding "on" 15 or energized periods with the proper polarities as selected.

Transmission of controls, preferred form.—Upon the transmission of the first impulse (following the conditioning impulse) relay SMR at the 20 field station is energized for actuating its polar contact 400 to the right or to the left depending upon the character of the impulse received. With lever SML in its normal position as illustrated, the (+) impulse applied to the S line 25 circuit actuates the contacts of relay F¹ to the right. A circuit is now closed for actuating the contacts of relay SMR to the right extending from (B+), contact 405 of relay F¹ in its right hand dotted position, back contacts 406 and 407 of 30 relays 3V¹ and 2V¹ respectively, front contact 108 of relay 1V¹ and winding of relay SMR to (CN). This energization of relay SMR closes contact 400 in its right hand position for applying energy to the normal operating winding of switch machine SM for operating the track switch to its 35 normal locked position.

In the event that lever SML is in its left hand dotted (reverse) position, the (-) impulse applied to the S line circuit actuates contact 405 40 of relay F¹ to the left which applies (B-) to the circuit above described including relay SMR. This positions contact 400 to the left for applying energy to the reverse operating winding of switch machine SM which operates the track switch to 45 its reverse locked position.

In a similar manner lever SGL in its neutral position causes relay PC to be picked up for applying a (+) impulse to the S line circuit when the second step is taken. This impulse actuates 50 contact 405 of relay F¹ to the right for applying (B+) to the winding of relay SGR over a circuit including front contact 407 of relay 2V¹. It is believed unnecessary to show or explain the 55 detailed operation of the circuits controlled by relay SGR since they form no part of the present invention.

Field start, preferred form.—This modification is of the coded duplex type and indications are transmitted from the station to the control office during the same cycle that controls are transmitted to the station.

Referring to Fig. 3, a change in the condition of the detector track section or a change in the condition of other traffic devices at the station may occur at any time and for convenience in describing the operation of this portion of the system it will be assumed that such change effects the de-energization of relay CH¹. The dropping of relay CH¹ closes a circuit for picking up relay PLA 65 which extends from (+), back contact 403 of relay CH¹, back contacts 404, 109 and 412 of relays 1V¹, 2V¹ and 3V¹ respectively and winding of relay PLA, to (-).

The picking up of relay PLA closes a circuit for energizing the A line circuit which extends from

the (+) terminal of the midtap of battery LB, winding of relay MA, A line conductor 40, front contact 402 of relay PLA, C line conductor 35, back contact 321 of relay STR and back contact 322 of relay PC, to the (-) terminal of battery 5 LB.

This energization of the A line circuit energizes relay MA and positions its polar contact 52 to the right which in turn closes a circuit for picking up relay STR extending from (+), back contact 313 of relay SA, back contact 314 of relay LV, contact 52 of relay MA in its right hand dotted position and lower winding of relay STR, to (-). Relay STR closes the previously described stick circuit for itself including its front contact 320 which maintains this relay energized until the end of the cycle. It will be noted that the picking up of relay STR opens the above described energizing circuit for relay MA, but before this relay has time to drop its contact 52 to 20 its neutral position for de-energizing the lower winding of relay STR, the stick circuit including the upper winding of relay STR is completed.

The closure of front contact 324 of relay STR closes the circuit including the S line conductor 25 and at front contact 328 the above described circuit for initially energizing relay PC is completed. The picking up of relay PC energizes the S line 30 circuit with a (+) impulse as in the previously described control cycle and in response to this impulse relays VP and VP¹ are energized. The picking up of relay VP opens the circuit including relay PC and this relay drops to terminate the conditioning "on" period. The system now 35 steps through a cycle of operations as before.

During the first "off" period (following the conditioning "on" period) relay 1V¹ at the station is picked up to deenergize the above described circuit including relay PLA. The switching of contact 404 from its back to its front point therefore makes relay PLA dependent for its energization upon the circuit controlled by the device which is to transmit indications.

Transmission of indications, preferred form.—After thus having initiated the system from the 45 field station the controls are transmitted as previously described to actuate the control relays in accordance with the positions of the control levers in the office. During the steps of the cycle indications are transmitted by relays PLA and PLB 50 selectively governing the energization of the A and B line circuits. For example, with track relay T energized when the first step is taken, the circuit leading to (+) at back contact 413 of relay T is open so that relay PLA will not be 55 picked up. When the control office energizes the S line circuit with a (+) impulse for the next (first) impulse period as previously described, the A line circuit is energized with a (-) impulse over a circuit extending from the (+) terminal of 60 battery LB, front contact 333 of relay PC, back contact 323 of relay NC, front contact 324 of relay STR, winding of relay F, S line conductor 334, front contact 422 of relay SA¹, back contact 402 of relay PLA, A line conductor 40 and winding of relay MA, to the mid-tap of battery LB. This positions the contacts of relay MA to their 65 left hand dotted positions and a circuit is closed for energizing relay 1IR and positioning its polar contact to its right hand position extending from (B+), resistance R, front contact 53 of relay PC, contact 54 of relay MA in its left hand dotted position, back contacts 55 and 56 of relays 3V and 2V respectively, front contact 57 of relay 1V and winding of relay 1IR, to (CN). This positions 70

75

contact 58 of relay 1IR to the right which maintains lamp OS de-energized as an indication that the track section is unoccupied.

In the event that the impulse applied to the S line circuit is (—) when this indication is transmitted to the control office, relay NC would be picked up and relay PC would be down. The A line circuit would then be energized over a circuit extending from the (+) terminal of the midtap of battery LB, winding of relay MA, A line conductor 40, back contact 402 of relay PLA, front contact 422 of relay SA¹, S line conductor 334, winding of relay F, front contact 324 of relay STR, front contact 323 of relay NC and back contact 322 of relay PC, to the (—) terminal of battery LB. Current flowing over this circuit energizes relay MA in the opposite sense and its polar contacts are positioned to the right. A circuit is now closed for energizing relay 1IR with (B+) potential which extends from (B+), resistance R, back contact 53 of relay PC, front contact 59 of relay NC, contact 54 of relay MA in its right hand dotted position and over the remainder of the previously described circuit to relay 1IR. Contact 58 of relay 1IR is in this instance again actuated to the right.

In the event that the track section is occupied, relay T is de-energized and its back contact 413 is closed. Relay PLA is picked up under this condition and (assuming the impulse applied to the S line circuit to be (+) a circuit is closed for energizing relay MA and actuating its polar contacts to the right which extends from the (+) terminal of the midtap of battery LB, winding of relay MA, A line conductor 40, front contact 402 of relay PLA, C line conductor 35, back contact 336 of relay NC and front contact 322 of relay PC, to the (—) terminal of battery LB. In this instance (relay MA actuated to the right and relay PC picked up) relay 1IR is energized with (B—) current for actuating its contact 58 to its left hand dotted position, which closes an obvious circuit for energizing lamp OS to indicate that the track section is occupied. This circuit for relay 1IR may be traced from (B—), front contact 60 of relay PC, contact 54 of relay MA in its right hand dotted position and over the previously described circuit to the winding of relay 1IR.

In the event that the S line circuit is energized with a (—) impulse when this indication is to be transmitted, relay NC will be picked up and relay PC will be down. Under this condition the A line circuit is energized with a (—) impulse over a circuit extending from the (+) terminal of battery LB, back contact 333 of relay PC, front contact 336 of relay NC, C line conductor 35, front contact 402 of relay PLA, A line conductor 40 and winding of relay MA, to the midtap of battery LB. Relay 1IR is energized from (B—) for positioning its contact 58 to its left hand dotted position over a circuit extending from (B—), back contact 60 of relay PC, front contact 61 of relay NC, contact 54 of relay MA in its left hand dotted position and over the previously described circuit to the winding of relay 1IR.

It will thus be seen that the channel circuits selected by the lower set of contacts on the stepping relay bank in the control office are selectively energized in accordance with the energized or de-energized conditions of relay PLA at the field station. A selected channel circuit is energized in accordance with the position of polar contact 54 of relay MA in combination with the energized or de-energized condition of the code

sending relays PC and NC, the latter energizing the S line circuit with impulses of positive and negative polarity respectively. In other words, current for selectively actuating the MA relay is derived from the S line circuit irrespective of whether the S line circuit is energized with (+) or (—) current, with a compensated arrangement effected by the PC or NC relay which is picked up for energizing the selected channel circuit with the proper polarity, irrespective of the position to which relay MA is actuated.

The above typical example indicates how a selection of one of two indications is transmitted at a particular step of the cycle over the A line circuit and it will be understood that additional indications are transmitted in the same manner when additional channel circuits are selected by front contacts 409 and 412 of relays 2V¹ and 3V¹, respectively, at the station and received by way of channel circuits in the office selected by front contacts 56 and 55 of relays 2V and 3V respectively.

A choice of one of two additional indications is transmitted at each step by selectively energizing the B line circuit. For example, assuming that relay M is de-energized, then when the first step is taken a circuit is closed for picking up relay PLB which extends from (+), back contact 114 of relay M, front contact 115 of relay 1V¹, back contacts 116 and 117 of relays 2V¹ and 3V¹ respectively and winding of relay PLB, to (—).

During the next energized period of the S line circuit (assuming it to be (+)), the B line circuit is energized with (+) potential over a circuit extending from the (+) terminal of the midtap of battery LB, winding of relay MB, B line conductor 50, front contact 401 of relay PLB, C line conductor 35, back contact 336 of relay NC and front contact 322 of relay PC, to the (—) terminal of battery LB.

Relay MB actuates its polar contact 62 to its right hand dotted position which closes a circuit for energizing relay 2IR extending from (B—), front contact 60 of relay PC, contact 62 of relay MB in its right hand dotted position, back contacts 63 and 64 of relays 3V and 2V respectively, front contact 65 of relay 1V and winding of relay 2IR, to (CN). Current flowing over this circuit actuates the polar contact of relay 2IR to its left hand position.

In the event that the S line circuit is energized with a (—) impulse when this indication is to be transmitted, then the B line circuit is energized with a (—) impulse for actuating polar contact 62 of relay MB to its left hand dotted position over a circuit extending from the (+) terminal of battery LB, back contact 333 of relay PC, front contact 336 of relay NC, C line conductor 35, front contact 401 of relay PLB, B line conductor 50 and winding of relay MB, to the midtap of battery LB. Relay 2IR is energized in the same direction as before over a circuit extending from (B—), back contact 60 of relay PC, front contact 61 of relay NC, contact 62 of relay MB in its left hand dotted position and over the previously described circuit to the winding of relay 2IR.

In the event that relay M is picked up, then relay PLB is de-energized during this first impulse and (assuming the S line circuit to be energized with a (+) impulse), the B line circuit is energized with a (—) impulse over a circuit extending from the (+) terminal of battery LB, front contact 333 of relay PC, back contact 323 of relay NC, front contact 324 of relay STR, winding of

relay F, S line conductor 334, front contact 422 of relay SA¹, back contact 401 of relay PLB, B line conductor 50 and winding of relay MB, to the midtap of battery LB.

- 5 Relay MB actuates polar contact 62 to its left hand dotted position for closing a circuit which energizes relay 2IR to its opposite position, which circuit extends from (B+), resistance R, front contact 53 of relay PC, contact 62 of relay MB 10 in its left hand dotted position and over the previously described circuit to the winding of relay 2IR.

In the event that the S line circuit is energized with a (−) impulse when this indication is to be transmitted, the B line circuit will be energized with a (+) impulse over a circuit extending from the (+) terminal of the midtap of battery LB, winding of relay MB, B line conductor 50, back contact 401 of relay PLB, front contact 422 of relay SA¹, S line conductor 334, winding of relay F, front contact 324 of relay STR, front contact 323 of relay NC and back contact 322 of relay PC, to the (−) terminal of battery LB. The actuation of contact 62 of relay MB to its right hand dotted position closes a circuit for again energizing relay 2IR with (+) potential, which circuit extends from (B+), resistance R, back contact 53 of relay PC, front contact 59 of relay NC, contact 62 of relay MB in its right hand dotted position and over the remainder of the previously described circuit, to relay 2IR.

- It will be understood that this selective energization of relay 2IR may be used for any desired indication purpose such, for example, as 35 indicating to the operator the condition of relay M at the field station. Although the transmission of a selection of any one of four indications has only been shown for the first step it will be understood that this arrangement may be employed for any number of steps desired by selecting a pair of channel circuits at each step by way of front contacts of the stepping relays, such as contacts 409 and 116 for the second step and contacts 412 and 117 for the third step. 40
- 45 During a cycle of operations for the transmission of indications, change relay CH¹ at the station is restored to its picked up position in readiness for any other change which may occur at the field station. The circuit arrangement for 50 accomplishing this result is not shown since it is immaterial for an understanding of the present invention and since various arrangements may be used for such accomplishment.

The restoration of the system to its normal 55 condition at the end of an indication cycle effects the deenergization of the various relays in the same manner described in connection with a control cycle.

- 60 Duplex operation.—It has been pointed out that control and indication cycles are initiated from the control office and the field station respectively. It has also been mentioned that indications of the existing conditions of the control devices at the station are transmitted to the office during the control cycle and controls are transmitted from the office to the station in accordance with the existing conditions of the control levers during an indication cycle. Therefore the resulting cycle of operations initiated from 65 the control office or from the field station results in two way transmission, or in other words, the duplex operation of the system.

Description of modification

- 70 The modification shown in Figs. 4, 5 and 6

makes use of a five wire line circuit, over which double the number of controls and indications (compared with the system of Figs. 1, 2 and 3) are transmitted. The same fundamental principle used in the system already described, that is, 5 the use of polar impulses derived from a source of current in the control office for the transmission of indications, is used in this modification.

The schematic circuit diagram of Fig. 4 shows the five wire line circuits and the apparatus most 10 closely associated with these line circuits. The S line, in combination with the A and B lines forming return paths for impulses in the S line, is used for controlling the stepping operation and for transmitting a choice of two controls at each 15 step. The A line, in combination with the B line as a return conductor, is used for transmitting a choice of two additional controls for each step. As indicated in the control office portion of this figure, line battery LB supplies energy for the 20 transmission of stepping impulses and one set of controls, the polarity of which are determined by the PC and NC relays. The controls transmitted over the A—B line circuit are made up of impulses from the source of current 2LB, with 25 the polarity determined by relay PX.

A choice of four indications is provided during the "off" periods by energizing the MA and MB line circuits with polar impulses selected at the field station, the polarity of which is supplied 30 from battery 2LB in the control office connected to the A and B line conductors. These four "off" indications are selected through back contacts of relay FP¹ at the field station as indicated by the legends "to other MAB (and to other MBB) indication contacts" as selected by the stepping relays. This refers to the fact that the MA and MB lines are conditioned through back contacts of relay FP¹. The back contacts of relay FP in the control office connect to relays MAB and MBB, 40 which relays are operated by the polar impulses applied to the respective line circuits.

During the "on" periods, when relays FP and FP¹ are picked up, additional indication circuits are selected as indicated by the legends which 45 refer to MAF and MBF indication contacts. The front contacts of relay FP in the office lead through relays MAF and MBF so that these relays may be selectively operated in accordance with the polar impulses applied to the MA and 50 MB lines respectively.

Control office equipment, modification

Referring to Fig. 5, the apparatus in the control office consists of the same stepping relay 55 bank as described in connection with the other modification and the same FP, SA, PC, NC and STR relays previously described. In this modification, however, a line relay FS is included in the S line circuit and a line relay FA is included in 60 the A line circuit. Furthermore, in place of the MA and MB relays of the previous arrangement, relays MAF, MAB, MBF and MBB are provided to receive the indication messages (double the number provided in the first modification) 65 from the field station. Relay PX is provided for determining the polarity with which the A—B line circuit is energized. Relays E and EP are impulse relays controlled in response to the stepping relay operation for energizing and deenergizing the A—B line circuit at the proper times. 70

Field station equipment, modification

The field station equipment is the same as in the first modification, except that relay FS¹ is 75

included in the S line circuit and relay FA¹ is included in the A line circuit. Resistance units 1R¹ and 2R¹ are provided for connecting the S line conductor to the A and B line circuits, by 5 means of which a drop in potential is provided for energizing the MA and MB line circuits during the transmission of indications.

In addition to the T and M relays at the field station, additional contacts 250 and 251 are provided for the purpose of indicating how a selection 10 of two indications are transmitted over the MA line circuit and a selection of two indications are transmitted over the MB line circuit during the "on" periods or the periods when relay FP¹ 15 is picked up. It will be understood that contacts 250 and 251 may be associated with any device from which it is desired to transmit indications.

Normal conditions, modification.—The system 20 is shown in Figs. 5 and 6 in its normal, at rest condition with the assumption that track relay T and change relay CH¹ are normally energized. Relay EP in the control office is normally energized over an obvious circuit through back contact 150 of relay E. The S line circuit, the MA 25 line circuit and the MB line circuit are normally deenergized, but the A—B line circuit is normally energized over a circuit extending from the (+) terminal of battery 2LB, back contact 151 of relay PX, front contact 153 of relay EP, winding of relay FA, A line conductor 160, winding of relay FA¹, resistance 1R¹, resistance 2R¹, B line conductor 170, front contact 154 of relay EP and back contact 155 of relay PX, to the (—) terminal of battery 2LB.

30 Relays FA and FA¹ are energized over this circuit, relay FA closing its front contacts and relay FA¹ closing its polar contact in a right-hand position.

Manual start, modification.—The system of this 40 modification is initiated from the control office in the same way as described in connection with the other modification, that is, a change relay (such as relay CH² of Fig. 2) is picked up in response to the actuation of the starting button, which 45 in turn causes relay STR to be picked up and stuck up until the end of the cycle in the manner previously described.

The picking up of relay STR closes a circuit 50 for picking up relay PC which extends from (+), front contact 156 of relay FA, back contacts 157, 158 and 159 of relays 3V, 2V and 1V respectively, front contact 161 of relay STR and winding of relay PC, to (—).

The picking up of relay PC applies (+) potential to the S line over a circuit extending from the (+) terminal of battery LB, back contact 162 of relay NC, front contact 163 of relay PC, winding of relay FS, S line conductor 180, winding of relay FS¹, resistance 1R¹, winding of relay FA¹, A line conductor 160, winding of relay FA, front contact 153 of relay EP, back contact 151 of relay PX, through the upper portion of battery 2LB, front contact 164 of relay PC and back contact 165 of relay NC, to the (—) terminal of battery LB. The voltage of battery LB is sufficient to overbalance that of the oppositely poled upper portion of battery 2LB. Furthermore, at the point between resistances 1R¹ and 2R¹ at the field station this circuit branches and returns through 70 resistance 2R¹, B line conductor 170, front contact 154 of relay EP, back contact 155 of relay PX, through the lower portion of battery 2LB, front contact 164 of relay PC and back contact 165 of relay NC, to the (—) terminal of battery 75 LB.

Current flowing over this circuit energizes the S line with (+) potential for picking up relay FS and for positioning relay FS¹ to the right. The response of relays FS and FS¹ effect the picking up of relays FP, SA, FP¹ and SA¹ in the same 5 manner described in connection with the previous modification. Furthermore, relays VP and VP¹ are picked up during this conditioning "on" period in the same manner previously described and it is believed unnecessary to repeat the description of this operation. It will be noted that a stick circuit is provided for relay SA through front contacts 186 of relay FA and 167 of relay SA. This is merely for the purpose of energizing the SA relay slightly in advance of its energization by relay FP, because relay FA picks up before relay FP at the beginning of each "on" 10 period.

Upon the response of relay VP a circuit is closed 15 for picking up relay E which extends from (+), back contacts 168, 169 and 171 of relays 3V, 2V and 1V respectively, front contact 172 of relay VP and winding of relay E, to (—). The opening of back contact 150 of relay E deenergizes relay EP and after a comparatively long time 20 interval, measured off by its slow acting characteristics, relay EP opens its front contacts 153 and 154 for deenergizing the A—B line conductors. Since the return path for the S line conductor 25 includes the A and B line conductors the S line 30 circuit is likewise deenergized to mark the end of the conditioning period.

Step-by-step operation, modification.—The step-by-step operations of the stepping relay banks in the control office and at the field station 35 are controlled by relays FP and FP¹ in the manner previously described in connection with the first modification so that it is considered unnecessary to repeat this description. The line impulsive operation in the first modification was 40 controlled by the stepping relays selecting the PC and NC relays direct. In the second modification the impulsive of the S line circuit is controlled by relays EP, PC and NC in combination. For example, the dropping of relay EP deenergizes 45 the line circuits to mark the end of the conditioning period as just described. The deenergization of the A line circuit deenergizes relay FA which opens, at its front contact 156, the circuit of the PC (or NC) relay, which in turn drops to maintain the S line circuit open, because the A—B 50 line circuit will be energized before the S line circuit to start the next impulse period.

The picking up of relay 1V during the first "off" period opens the above described circuit of relay 55 E and this relay drops to close the pick up circuit for relay EP. Upon the response of relay EP the A—B line circuit is energized as previously traced, resulting in the picking up of relay FA which closes at its front contact 156 the circuit 60 for energizing the next PC or NC relay for sending the next impulse out over the S line circuit.

It will thus be seen that the dropping of relay EP de-energizes the S line circuit by opening both the A and B line conductors and that 65 when relay EP again picks up, the A and B line conductors are again energized but the S line conductor is not energized until the response of relays FA and PC (or NC).

Polarity selection of control impulses, modification.—When the system of this modification is initiated from the control office as above described the first (conditioning) impulse applied to the S line circuit is (+) in character by reason of the picking up of relay PC. The A line circuit is nor- 70 75

mally energized with current of (+) character but during the conditioning impulse the positions of relays FS¹ and FA¹ at the field station are immaterial because the first channel circuit is not selected until during the deenergized or "off" period following the conditioning impulse.

Assuming that lever SML is in its normal position as shown in Fig. 5, it will be obvious that relay PC is picked up to apply a (+) impulse to the S line circuit on the second step because of the selection through front contact 159 of relay 1V just prior to this impulse period. In the event that lever SML is in its left-hand reverse position, relay NC is energized to apply a (-) impulse to the S line circuit because of the reversed positions of the pole changing contacts on relays PC and NC.

This selection of the polarity of energization for the S line circuit occurs on each step by reason 20 of the selection made at front contacts 159, 158 and 157 of relays 1V, 2V and 3V respectively. This arrangement is in accordance with the previously described modification and it will be understood that these polar impulses operate relay FS¹ to the right or left for energizing (by means of contact 175) the control relays selected through contacts of the stepping relays, all in the same manner previously described.

During the stepping operations at the control 30 office and at the field station the A-B line circuit is energized at each step from battery 2LB with a polarity selected by relay PX. For example, the first impulse (following the conditioning impulse) applied to the A line conductor is (+) in character because relay PX is deenergized due to the circuit selected through front contact 173 of relay 1V leading to lever 3L, for example, which is in a position for disconnecting the (+) terminal of the local battery source from the circuit leading to relay PX. With relay PX deenergized 40 it is obvious that the (+) terminal of battery 2LB is connected to the A line conductor and the (-) terminal of this battery is connected to the B line conductor.

45 Assuming another control device, such as lever 4L, to be in the position indicated, then relay PX is energized over a circuit including front contact 174 of relay 2V so that the A line circuit is energized during the next impulse period with a (-) impulse because of the reversed position of pole changing contacts 151 and 155 of relay PX. This transmission of polar impulses over the A line circuit actuates relay FA¹ at the field station to its right and left hand positions for selectively energizing (by means of contact 185) additional channel circuits which may be lead to control relays, all of which is indicated by the bracket bearing the legend "To control relays".

It is believed unnecessary to show or explain 60 the detailed operation of the control relays connected to the channel circuits indicated, since this operation may be understood by referring to the operation of contact 405 of relay F¹ of Fig. 3, remembering that contacts 175 and 185 of relays 65 FS¹ and FA¹ are selectively actuated in response to control impulses applied to the S line and the A line circuits respectively.

Field start, modification.—This modification is 70 of the coded duplex type so that indications are transmitted from the station to the control office during the same cycle that controls are transmitted to the station. For conveniently describing the operation of this modification for the transmission of indications it will first be explained how a change in conditions at the field

station initiates the system. It will then be obvious from the discussion of the first modification how the system functions for duplex operation irrespective of whether a cycle of operations is initiated from the control office or from the 5 field station.

Referring to Fig. 6, a change in the condition of a traffic device at the station effects the de-energization of relay CH¹ in a manner previously described. The dropping of relay CH¹ closes a 10 circuit for energizing the MB line conductor which circuit may be traced (recalling that the A line conductor is connected to the (+) terminal and the B line conductor is connected to the (-) terminal of battery 2LB) from the (+) 15 terminal of the midtap of battery 2LB, winding of relay MBB, back contact 176 of relay FP, back contact 177 of relay FS, MB line conductor 178, back contact 181 of relay FP¹, back contacts 182, 183 and 184 of relays 3V¹, 2V¹ and 1V¹ respectively, back contact 186 of relay CH¹, B line conductor 170, front contact 154 of relay EP and back contact 155 of relay PX, to the (-) terminal of battery 2LB. Current flowing over this circuit actuates polar contact 152 of relay MBB to the 25 right which effects the energization of relay STR over a circuit not shown but which is the same as controlled by polar contact 52 of relay MA of Fig. 2.

The picking up of relay STR closes the previously described circuit for energizing relay PC, which applies a (+) impulse to the S line circuit as described in connection with a control cycle. Relays FS, FP, FS¹ and FP¹ are picked up as before and upon the response of relay FP¹ the 35 MB line conductor is de-energized at back contact 181. This of course deenergizes relay MBB but polar contact 141 of this relay has not effected an IR relay operation because the first stepping relay has not yet responded. 40

When relay EP in the control office drops during this first (conditioning) impulse period the A-B line circuit is de-energized as before. This drops relays FA and FA¹. Since the S line conductor has no return path to the battery in the 45 control office, because of open front contacts 153 and 154, the S line circuit is likewise deenergized. This drops relays FS and FS¹ to mark the end of the conditioning "on" period. Relay PC is deenergized when relay FA opens its front 50 contact 156.

It will thus be seen that the system is initiated from the field station by the momentary energization of line MB with a (+) impulse for positioning the contacts of relay MBB to the right, 55 after which the S line circuit is energized with a (+) impulse for the conditioning period. Following the termination of the conditioning period the system steps through its cycle as previously described, with double controls being transmitted over the S line circuit and over the A-B line circuits.

Transmission of indications, modification.—The indication circuits selected through back contacts 181 and 191 of relay FP¹ are conveniently referred to as "off" indications, since these indications are conditioned during the deenergized periods of the S line circuit, during which periods relays FP and FP¹ are down.

When relay EP in the control office picks up 70 to close its front contacts 153 and 154 for energizing the A-B line circuit, the MA line conductor is energized with a (+) polarity for transmitting a first choice "off" indication. The circuit for energizing line MA may be traced from 75

the (+) terminal of the midtap of battery 2LB, winding of relay MAB, back contact 187 of relay FP, back contact 188 of relay FS, MA line conductor 179, back contact 191 of relay FP¹, back contacts 252 and 253 of relays 3V¹ and 2V¹ respectively, front contact 254 of relay 1V¹, front contact 255 of relay T, B line conductor 170, front contact 154 of relay EP and back contact 155 of relay PX, to the (-) terminal of battery 2LB.

This actuates the contacts of relay MAB to their right-hand dotted positions, and assuming that relay PX is deenergized, a circuit is closed for energizing channel conductor 190, which circuit may be traced from (B+), resistance 5R, back contact 189 of relay PX, contact 192 of relay MAB in its righthand dotted position, back contacts 193 and 194 of relays 3V and 2V respectively and front contact 195 of relay 1V, to conductor 190. It will be understood that conductor 190 may lead to an indication receiving relay such as relay 1IR of Fig. 2.

In the event that relay PX is picked up for transmitting a (-) control over the A line circuit when this indication is to be transmitted, then relay MAB actuates its polar contacts to the left over the previously described circuit from the midtap of battery 2LB by way of the MA and the B line conductors, but in this instance through front contact 151 of relay PX, to the (+) terminal of battery 2LB. With contact 192 in its left-hand dotted position channel conductor 190 is energized with (+) potential over a circuit extending from (B+), resistance 5R, front contact 199 of relay PX, contact 192 of relay MAB in its left-hand dotted position and over the previously described circuit, to conductor 190.

In the event that track relay T is deenergized, then the circuit above described for energizing line MA extends through back contact 255 of relay T, over the A line conductor to the (+) terminal of battery 2LB (assuming relay PX down) by way of back contact 151 of relay PX. This positions contact 192 of relay MAB to its left-hand dotted position and since relay PX is down, (B-) is connected to channel conductor 190 over a circuit extending from (B-), resistance 6R, back contact 199 of relay PX, contact 192 of relay MAB in its left-hand dotted position and over the previously described circuit, to conductor 190.

In the event that relay PX is picked up when this indication is transmitted, relay MAB actuates its contact 192 to the right because the previously described circuit extending from the midtap of battery 2LB through the winding of relay MAB is connected to the A line circuit at back contact 255 of relay T and to the (-) terminal of battery 2LB through front contact 155 of relay PX. Since relay PX is up and contact 192 of relay MAB is to the right, (B-) is connected through front contact 189 of relay PX and contact 192 of relay MAB in its right-hand dotted position to channel conductor 190.

The above examples indicate how a choice of two indications are transmitted over the MA line circuit for selectively energizing a channel circuit (190) from the battery in the office which is reversibly connected to the A-B line circuit leading from the office to the station. This choice of two indications derived from the central office battery selectively energizes the selected channel circuit with one or another polarity, irrespective of the polarity with which the

A-B line circuit is energized from the control office, even though the polarity for the indication is derived from this control office battery.

An additional choice of two indications are obtained when relays FP and FP¹ are picked up by selectively energizing the MA line circuit. For example, when relay E in the control office is picked up during the first impulse period the MA line conductor is energized over a circuit extending from the midtap of battery 2LB, winding of relay MAF, front contact 187 of relay FP, front contact 188 of relay FS, front contact 198 of relay E, MA line conductor 179, front contact 191 of relay FP¹, back contacts 200 and 201 of relays 3V¹ and 2V¹ respectively, front contact 202 of relay 1V¹, back contact 250, A line conductor, winding of relays FA¹ and FA, front contact 153 of relay EP and back contact 151 of relay PX (assumed down) to the (+) terminal of battery 2LB. This actuates polar contact 196 of relay MAF to the left and (B-) is connected to channel circuit 197 over a circuit extending through resistor 6R, back contact 199 of relay PX, contact 196 of relay MAF in its left-hand dotted position and over an obvious channel selecting circuit to channel conductor 197.

In the event that relay PX is picked up when this indication is transmitted, then the circuit traced from the midtap of battery 2LB through the winding of relay MAF by way of the A line conductor returns to the (-) terminal of this battery through front contact 155 of relay PX. (B-) is in this instance applied to channel conductor 197 through front contact 189 of relay PX and through contact 196 of relay MAF in its right-hand dotted position, because relay MAF is energized in an opposite sense from that previously described.

In the event that contact 250 is in its alternate position (and PX down) for connecting with the B line conductor when this indication is transmitted, the circuit leading from the midtap of battery 2LB through the winding of relay MAF extends by way of front contact 250 and the B line conductor to the (-) terminal of battery 2LB because relay PX has its back contact 155 closed. This actuates contact 196 of relay MAF to the right and a (B+) potential is applied to conductor 197 through back contact 189 of relay PX and contact 196 of relay MAF in its right-hand dotted position. In the event that relay PX is picked up when front contact 250 is effective, then the circuit from the midtap of battery 2LB extends through the winding of relay MAF, front contact 250, B line conductor and front contact 151 of relay PX to the (+) terminal of battery 2LB. This actuates polar contact 196 of relay MAF to the left and in this instance (B+) potential is applied to conductor 197 through front contact 199 of relay PX and contact 196 of relay MAF in its left-hand dotted position.

The above examples indicate how a choice of two indications are transmitted over the MA line circuit during the picked up conditions of relays FP¹ and FP. These two indications, plus the previously described choice of two indications effective when relays FP and FP¹ are deenergized, provide a choice of four indications per step. It will now be explained how the MB line circuit is similarly conditioned for transmitting an additional choice of four indications.

From the above it will be observed that the MA line is energized with a selected polar impulse

between the picking up of relay EP and the picking up of relay FS for one group of "off" indications. It will also be noted that the MA line is energized with a selected polar impulse between the picking up of relay E and the dropping of relay EP during the "on" period for one group of "on" indications. It will now be explained how the MB line is energized with a selected polar impulse between the picking up of relay EP and the picking up of relay FS for another group of "off" indications. Also how the MB line is energized with a selected polar impulse between the picking up of relay E and the dropping of relay EP for another group of "on" indications.

Assuming the first step to have been taken, that is, relays IV and IV¹ picked up and that relays FP and FP¹ are down, with contact 203 of relay M in the position shown the MB line circuit is energized with a (—) impulse over a circuit extending from the midtap of battery 2LB, winding of relay MBB, back contact 176 of relay FP, back contact 177 of relay FS, MB line conductor 178, back contact 181 of relay FP¹, back contacts 182 and 183 of relays 3V¹ and 2V¹ respectively, front contact 184 of relay IV¹, back contact 203 of relay M, winding of relay FA¹, A line conductor 160, winding of relay FA, front contact 153 of relay EP and back contact 151 of relay PX (assuming relay PX to be down) to the (+) terminal of battery 2LB. This actuates the polar contacts of relay MBB to their left-hand dotted positions and a circuit is closed for energizing channel conductor 140 with a (—) polarity which circuit extends from (B—), resistance 6R, back contact 199 of relay PX, contact 141 of relay MBB in its left-hand dotted position and over the channel selecting circuit of the stepping relays to conductor 140.

In the event that relay PX is picked up when this indication is transmitted, the MB line conductor is energized with a (+) impulse over a circuit extending from the midtap of battery 2LB, winding of relay MBB and over the previously described circuit, including A line conductor 160, to the (—) terminal of battery 2LB by way of front contact 155 of relay PX. In this instance conductor 140 is energized with (—) potential over a circuit extending from (B—), resistance 6R, front contact 189 of relay PX, contact 141 of relay MBB in its right-hand dotted position (because of the (+) impulse applied to line MB) and over the remainder of the previously described circuit to conductor 140.

In the event that relay M is energized when this indication is transmitted (with relay PX down), the MB line conductor is energized with a (+) impulse for positioning the contacts of relay MBB to their right-hand dotted positions. This circuit may be traced over the previously described circuit from the midtap of battery 2LB, including the winding of relay MBB (but this time through front contact 203 of relay M), to B line conductor 170 and thence to the (—) terminal of battery 2LB by way of back contact 155 of relay PX. Channel conductor 140 is energized with a (+) potential under this condition over a circuit extending from (B+), resistance 5R, back contact 189 of relay PX, contact 141 of relay MBB in its right-hand dotted position and over the channel selecting circuit to conductor 140.

In the event that relay PX is picked up when this indication is transmitted, then the MB line conductor is energized with a (—) impulse which is effective to position the contacts of relay MBB

to their left-hand dotted positions over a circuit extending from the midtap of battery 2LB, winding of relay MBB, and over the previously described circuit including front contact 203 of relay M and B line conductor 170, to the (+) terminal of battery 2LB by way of front contact 151 of relay PX. Channel conductor 140 is energized with a (+) potential over a circuit extending from (B+), resistance 5R, front contact 199 of relay PX, contact 141 of relay MBB in its left-hand dotted position and over the channel selecting circuit to conductor 140.

The next indication is transmitted when relay E picks up its contacts to connect the MB line conductor by way of front contact 148 of relay E and front contact 177 of relay FS to relay MBF by way of front contact 176 of relay FP. Under this condition relays FP and FP¹ will be picked up and assuming contact 251 (Fig. 6) in the position shown, the MB line circuit is energized with a (—) impulse over a circuit extending from the midtap of battery 2LB, winding of relay MBF, front contact 176 of relay FP, front contacts 177 and 149 of relays FS and E respectively, MB line conductor 178, front contact 181 of relay FP¹, back contacts 142 and 143 of relays 3V¹ and 2V¹ respectively, front contact 144 of relay IV¹, back contact 251, winding of relay FA¹, A line conductor 160, winding of relay FA, front contact 153 of relay EP and back contact 151 of relay PX (assuming relay PX to be down), to the (+) terminal of battery 2LB.

This (—) impulse over the MB line circuit actuates the polar contact of relay MBF to its left-hand dotted position for energizing channel conductor 130 with a (—) potential over a circuit extending from (B—), resistance 6R, back contact 199 of relay PX, contact 149 of relay MBF in its left-hand dotted position and over the channel selecting circuit of the stepping relays to conductor 130. In the event that relay PX is picked up when this indication is transmitted, the MB line conductor will be energized with a (+) impulse to position the polar contact of relay MBF to its right-hand dotted position, over a circuit extending from the midtap of battery 2LB, winding of relay MBF and over the previously described circuit including back contact 251 and A line conductor 160, to the (—) terminal of battery 2LB by way of front contact 155 of relay PX. Channel conductor 130 is energized with a (—) potential under this condition over a circuit extending from (B—), resistance 6R, front contact 189 of relay PX, contact 149 of relay MBF in its right-hand dotted position and over the channel selecting circuit to conductor 130.

In the event that contact 251 is closed in its alternate position, then the indication transmitted at this point consists of a (+) impulse applied to the MB line conductor over a circuit extending from the midtap of battery 2LB, winding of relay MBF and over the previously described circuit including front contact 251 and B line conductor 170 to the (—) terminal of battery 2LB, by way of back contact 155 of relay PX (assuming relay PX to be down). With polar contact 149 of relay MBF in its right-hand dotted position and relay PX down, channel conductor 130 is energized with a (+) potential over a circuit extending from (B+), resistance 5R, back contact 189 of relay PX, contact 149 of relay MBF in its right-hand dotted position and over the channel selecting circuit to conductor 130.

In the event that relay PX is picked up when

this indication is transmitted the MB line conductor will be energized with a (–) impulse to actuate polar contact 149 to its left-hand dotted position, over a circuit extending from the mid-
5 tap of battery 2LB, winding of relay MBF and over the previously described circuit including front contact 251 and B line conductor 170 to the (+) terminal of battery 2LB, by way of front contact 151 of relay PX. Channel conductor 130
10 is energized with (+) potential under this condition over a circuit extending from (B+), resistance 5R, front contact 199 of relay PX, contact 149 of relay MBF in its left-hand dotted position and over the channel selecting circuit to
15 conductor 130.

It is believed that the above examples are sufficient to indicate how a choice of four indications per step is effective to energize four channel circuits such as conductors 190, 197, 140 and 130
20 each with one or another polarity as determined by the conditions of corresponding channel circuits at the field station. In other words, four out of eight indication conditions are selectively transmitted on each step of the cycle. It will be
25 understood that other channel circuits selected at other steps of the cycle are likewise conditioned in the same manner.

Having thus described a centralized traffic controlling system as a preferred form and another
30 and specific embodiments of the present invention, it is desired to be understood that these forms are selected to facilitate in the disclosure rather than to limit the number of forms which the invention may assume and it is further to be
35 understood that various modifications, adaptations, and alterations may be applied to the specific forms shown to meet the requirements of practice without departing from the spirit of the invention except as limited by the appended
40 claims.

What I claim is:

1. In a remote control system; a pair of control line conductors and an indication line conductor extending from a control office to a distant field station; devices at said station; means including a source of current in said office for applying a series of time spaced control impulses to a line circuit including said control line conductors; control transmitting means in said office for reversibly connecting said source of current to said control line conductors, whereby said control impulses are marked with either of two polarities; means at said station selectively responsive to the polarity of said control impulses
45 for selectively controlling said devices; indication transmitting means including a connection from an intermediate point of said source to said indication conductor at said office and contacts at said station for selectively connecting said indication line conductor in a circuit with either of said control line conductors and a portion of said battery, whereby distinctive indication impulses are transmitted to said office; indication receiving means in said office responsive to said indication impulses; and compensating means
50 controlled by said control transmitting means and said indication receiving means, whereby each distinctive indication impulse is identically registered irrespective of the polarity of energization of said control line conductors which effect the transmission of said indication impulses.

2. In a remote control system; a pair of control line conductors and an indication line conductor extending from a control office to a distant field
75 station; governing devices at said station; means

including a source of current in said office for applying a series of time spaced control impulses to a control circuit including said control line conductors; control transmitting means in said office for reversibly connecting said source of current to said control circuit, whereby said control impulses are marked with either of two polarities; means at said station selectively responsive to the polarity of said control impulses for selectively controlling said governing devices; indication transmitting means including a connection in said office between said indication line conductor and an intermediate point of said source and including contacts at said station for selectively connecting said indication line conductor in circuit with either of said control line conductors concomitantly with the application of said control impulses and time spaces to said control line conductors, whereby distinctive indication impulses are transmitted to said office of a polarity depending on both the polarity applied to said control circuit and on the particular control line conductor with which said indication line conductor was connected in series; and indication receiving means in said office controlled so as to be responsive to said selective connection of said indication line conductor to said control line conductors irrespective of the polarity applied to the control line conductor during that particular impulse.

3. In a remote control system; a pair of control line conductors and an indication line conductor extending from a control office to a distant field station; governing devices at said station; control transmitting means including a source of current in said office for applying a series of time spaced control impulses to a control circuit including said control line conductors; control transmitting means in said office for reversibly connecting said source of current to said control circuit, whereby said control impulses are marked with either of two polarities; means at said station selectively responsive to the polarity of said control impulses for selectively controlling said governing devices; means for connecting the of-
45 fice end of said indication line conductor to an intermediate point of said source, indication transmitting means at said station for selectively connecting said indication line conductor to either of said control line conductors concomitantly with the application of said control im-
50 pulses to said control line conductors to transmit distinctive indication impulses to said office over an indication circuit including said indication line conductor; indication receiving means in
55 said office effective during the application of said control impulses responsive to said indication im-
pulses; and compensating means controlled by said control transmitting means and said indication receiving means, for registering an indica-
60 tion character which is the source irrespective of the polarity of energization of said control line conductors which constituted the current source for the transmission of said indication im-
65 pulses.

4. In a remote control system; a pair of control line conductors and a pair of indication line conductors extending from a control office to a distant field station; governing devices at said station; means including a source of current in said office for applying a series of time spaced control impulses to said control line conductors; control transmitting means in said office for reversibly connecting said source of current to said control line conductors to constitute an ener-
70
75

gized control circuit, whereby said control impulses are marked with either of two polarities; means at said station selectively responsive to the polarity of said control impulses for selectively controlling said governing devices; means at said office for connecting both of said indication line conductors to an intermediate point of said source, indication transmitting means at said station for selectively connecting either of said indication line conductors to either of said control line conductors, whereby distinctive indication impulses are transmitted to said office; indication receiving means in said office selectively responsive to said indication impulses; and compensating means controlled by said control transmitting means and said indication receiving means to deliver identically the same indication character irrespective of the polarity of energization of said control line conductors which constituted the current source for the transmission of said indication impulses.

5. In a remote control system, a first and a second line wire extending from a control office to a distant field station, devices at said station, means including a source of current in said office for selectively applying positive or negative time spaced control impulses to a first line circuit including said first line wire and a common wire, manually operable means in said office for determining the positive or negative character of each control impulse, means at said station controlled in accordance with the character of said impulses for selectively controlling said devices, indication devices in said office, means including an automatically operable indication contact and a connection between said second line wire and said source of current for selectively applying positive or negative time spaced indication impulses to a second line circuit from either said first line wire or said common wire, said second circuit including said second line wire of which the polarity of these impulses is dependent upon the polarity applied to said first line circuit and also upon the condition of said indication contact, electro-responsive means in said office selectively controlled in accordance with the character of said indication impulses, and means in part controlled by said manually operable means for interpreting said indication impulses by compensating for the polarity applied to said first line circuit.

6. In a remote control system; a first, a second and a third line wire extending from a control office to a distant field station; devices at said station; means including a source of current in said office for selectively applying positive or negative time spaced control impulses to a first line circuit including said first line wire and a common wire; manually controllable means in said office for determining the positive or negative character of each control impulse applied to said first line circuit; means at said station controlled in accordance with the character of said control impulses for selectively controlling said devices; indication devices in said office; means including a connection between said second and third line wires and said source of current and automatically operable

means at said stations for selectively applying positive or negative time spaced indication impulses derived from either said first line wire or said common wire to a second line circuit including said second line wire and a third line circuit including said third line wire; means including said manually and said automatically operable means for determining the positive or negative character of each indication impulse; and circuit means in said office selectively controlled in accordance with the character of said indication impulses and the condition of said manually controllable means to compensate for the polarity of current applied to said first line circuit.

7. In a remote control system, a control office and a field station connected by a control line circuit and an indication line circuit, means for applying impulses of current of positive and negative polarity to said control line circuit, step by-step mechanisms at said office and at said station operable in synchronism by said impulses irrespective of their polarity, a controlled device and a device to be indicated at said station, means responsive to the polarity of one of said impulses for selectively controlling said controlled device, means for applying an impulse to said indication line circuit from current derived from said control line circuit and of a polarity dependent on both the polarity then existing on the control line circuit and the condition of the device to be indicated which device to be indicated may either connect the control line circuit directly or reversibly to the indication line circuit, and means responsive to the polarity of the impulse applied to said indication line circuit modified by the polarity applied to said control line circuit on the same step for indicating the condition of said device to be indicated.

8. In a remote control system, a control office and a field station connected by a control line circuit and an indication line circuit, means for applying impulses of current of positive and negative polarity to characterize a code to said control line circuit, step-by-step mechanisms at said office and at said station operable in synchronism by said impulses irrespective of their polarity, control devices at said field station, other devices at said station having indications to be transmitted, means responsive to the polarity of said impulses for selectively controlling said controlled devices, means for applying impulses to said indication line circuit from current derived from said control line circuit each of a polarity dependent on both the polarity applied to the control line circuit on a particular step and the condition of the other device at said station to be indicated on that step which other device may connect the control line circuit directly or reversibly to the indication line circuit, and means responsive to the polarities of the impulses applied to said indication line circuit each modified by the polarity applied to said control line circuit on the same step for indicating the condition of said other devices.

NEIL D. PRESTON.
